KASIMIR SCHROTT, OF MAGDEBURG, GERMANY, ASSIGNOR TO THE FIRM FRIED. KRUPP
GRUSONWERK AKTIENGESELLSCHAFT, OF MAGDEBURG-BUCKAU, GERMANY

LEAD CABLE PRESS

Application filed February 29, 1928, Serial No. 258,124, and in Germany March 15, 1927.

This invention relates to lead cable presses. In order to sheath cables of different diameters with one and the same press, hitherto all the pressing heads have had to be changed. 5 This changing of the pressing heads, however, is a very tedious process and requires time, thus entailing a substantial increase in the cost of working. In order to obviate this drawback attempts have already been made 10 in connection with the sheathing of both thin and thick cables to work with only one press head by using different mandril holders adapted, as regards their inner diameter, to the actual diameter of the cable to be 15 sheathed. The result of these attempts however has been that with an increasing difference between the external diameter of the mandril holder and the inner diameter of the mandril the further screwing in of the mandril holder, necessary for reducing the thickness of the lead sheath, becomes increasingly difficult owing to the increasing pressure and friction surface, and finally it cannot be effected at all when the press has once been 20 subjected to pressure and consequently has lead in its lead chamber. This latter drawback also occurs in particular when a relatively thin cable has to be sheathed, because in this case the annular surface of the mandril 25 holder with mandril, working in opposition to the lead contained in the lead chamber, has to be very large.

In order to overcome the drawbacks mentioned above, at least one of the mandril 30 holders is, according to the present invention so constructed that there can be inserted therein a second mandril holder intended for the reception of a thinner cable than that ordinarily received by the first mandril 35 holder, thus rendering it possible to effect a relatively easy adjustment of the mandril holder even in the case of a great difference between its external diameter and the inner diameter of the mandril.

40 It is especially advantageous, as mentioned again hereinafter, to construct the mandril holders so that they are divided transversely in relation to their longitudinal axes.

In order that the said invention may be 45 clearly understood and readily carried into

effect the same will now be described more fully with reference to the accompanying drawings which illustrate two pressing heads of a vertical lead cable press and in which:—

Figure 1 is a vertical section taken through 55 the central axis of the mandril holder.

Figure 2 is a vertical section corresponding to Figure 1 but showing a second mandril holder inserted, and

Figure 3 is a part section corresponding to 60 Figure 2 but with a divided mandril holder.

Between the two halves 1 and 2 of the press head divided parallel to the central axis of the tool holder there are mounted in the usual way upon one side the matrix holder 3 with the insertion member 4 and the matrix 5, and upon the opposite side the mandril holder 6 with the mandril 7. With the dimensions indicated in Figure 1 for the inner diameter of the parts, the press head is arranged for 70 sheathing or covering a relatively thick cable. If now a thin cable is to be sheathed, the mandril holder 6 is taken out and upon it, in place of the mandril 7, there is fitted an adjustment member 8 and into the mandril holder 6 which 75 is provided with an internal screw thread 6' there is screwed a second mandril holder 9 with its mandril 10, the bore of both of which is such as to correspond to the thickness of the thinner cable that is now to be sheathed. 80

After the matrix holder 3 has also been provided with an insertion member 4' and a matrix 5' of smaller bore the pressing process can be commenced. The necessary adjustment between the mandril 10 and the matrix 85 5', for the purpose of fixing precisely the thickness of the lead sheath, is now effected solely by displacing the mandril holder 9. If instead of the two mandril holders 6, 9 only 90 a single mandril holder were provided, then owing to the large annular cross section working in opposition to the lead in the lead chamber the screwing-in of this mandril holder would be practically impossible. The mandril holder 9, on the contrary, works merely 95 with a relatively small annular cross section upon the lead contained in the lead chamber and can, consequently, be screwed into position without difficulty, while the mandril 100

holder 6 rests with its head upon the pressing head and remains stationary.

- The mandril holders are preferably divided transversely in relation to their longitudinal axes, as a result of which a further reduction in the work entailed in screwing the mandril holder into position is effected. If a lead cable press has during a pressing process once been subjected to the very high pressure usual with such presses, then a rotation of the parts in intimate contact with the lead is only rendered possible with a maximum expenditure of labour. This is due to the strong adhesion of the lead and more especially to the lead forcing its way between the mandril holder and the pressing head. A mere displacement however of the mandril holder involves, in comparison with a displacement by rotation, a substantial simplification of the operation.
- 20 In Figure 3 the mandril holders are shown divided. Upon rotation of one of the external parts 11 or 12 of the mandril holder, the inside parts 13 and 14 (so-called cartridges) do not participate, so that the conical surfaces 25 of the mandril or of the mandril holder coming in contact with the lead do not rotate but are only displaced axially. The friction between the annular surfaces of the two mandril holder parts is relatively slight and can thus 30 be easily overcome. In order to withdraw the cartridges from the pressing head they are provided with an inner screw thread 13' or 14' into which a bolt can be screwed when they are to be withdrawn.
- 35 In the claims which follow the terms "relatively large" and "relatively small" are used to compare the inner diameter of the outer mandril holder with the inner diameter of the inner mandril holder.
- 40 Having now particularly described and ascertained the nature of my said invention and in what manner the same is to be performed, I declare that what I claim is:—
1. In a lead cable press, a press head, a die 45 mounted therein, a mandril holder of relatively large inner diameter mounted in said press head so as to be adjustable toward and from said die, and a second mandril holder of relatively small inner diameter adjustably 50 mounted within said first mentioned mandril holder.
2. In a lead cable press, the combination with a mandril holder of relatively large inner diameter of a second mandril holder fitting within the first and adjustable relative thereto.

KASIMIR SCHROTT.
